UNITED STATES PATENT OFFICE.

JULIUS BERBECKER, OF NEW YORK, N. Y.

CURTAIN-POLE RING.

SPECIFICATION forming part of Letters Patent No. 295,972, dated April 1, 1884.

Application filed February 13, 1884. (No model.)

To all whom it may concern:

Be it known that I, JULIUS BERBECKER, of the city, county, and State of New York, have invented certain new and useful Improvements in Curtain-Pole Rings, of which the following is a specification.

This invention relates to certain improvements in the curtain-pole ring for which Letters Patent of the United States have been granted heretofore to William Lang, of Brooklyn, New York, No. 286,712, and dated October 18, 1883, whereby the construction of said ring is rendered cheaper, simpler, and more durable; and the invention consists of a curtain-pole ring that is connected at the end by a clamping-sleeve having an eye made integral therewith and bent up at right angles to the body of the sleeve.

In the accompanying drawings, Figure 1 represents a side view; Fig. 2, a vertical transverse section on line x x , Fig. 1, of my improved curtain-pole ring; and Fig. 3 is a detail top view of the blank from which the clamping-sleeve is made.

Similar letters of reference indicate corresponding parts.

A in the drawings represents the body of a curtain-pole ring, which is made of a tube of brass or other suitable sheet metal, and jointed at the abutting ends by a clamping-sleeve, B, that is tightly closed over the ends of the ring A. The clamping-sleeve B is provided with an eye, C, which is made integral with the

sleeve B, and which is bent up at right angles thereto when the sleeve is applied to the ring. 35 For this purpose the sleeve-blank B', Fig. 3, is provided with an eye, C', which is cut by suitable dies from brass or other suitable material, the blank being bent into sleeve shape, so as to close tightly around the ends of the 40 ring. The eye C' is first bent outwardly at right angles to the body of the sleeve, as shown clearly in Figs. 1 and 2. As the eye is integral with the sleeve, it cannot become detached or play loose, which has been the case heretofore, as the eye was attached by a pronged 45 shank to a recess of the sleeve.

Having thus described my invention, I claim as new and desire to secure by Letters Patent—

1. A curtain-pole ring consisting of a ring-shaped tube and of a clamping-sleeve applied to the abutting ends of the tube, said clamping-sleeve being provided with an eye extending at right angles therefrom, and being made integral therewith, substantially as set forth. 50 55

2. A clamping-sleeve for curtain-pole rings made from a blank, having an eye made integral therewith, and bent outwardly at right angles to the sleeve, substantially as described.

In testimony that I claim the foregoing as 60 my invention I have signed my name in presence of two subscribing witnesses.

JULIUS BERBECKER.
